UNITED STATES PATENT OFFICE.

JOHN T. WATTS, OF LOS ANGELES, CALIFORNIA.

PAIR OF SUSPENDERS.

Application filed May 18, 1921. Serial No. 470,554.

To all whom it may concern:

Be it known that I, JOHN T. WATTS, a citizen of the United States, residing at Los Angeles, in the county of Los Angeles, State 5 of California, have invented a new and useful Pair of Suspenders, of which the following is a specification.

My invention relates to suspenders such as are commonly used for supporting trousers and the like and the principal object 10 of my invention is to produce such an article of simple form and construction so arranged that no pressure is placed upon the back bone of the wearer, a further object being to make an article of the class described 15 which is readily and automatically adjustable to the movement of the wearer.

Referring to the drawings, which are for 20 illustrative purposes only,

Fig. 1 is an illustrative view of the suspenders as worn, the view showing the back of the suspenders.

Fig. 2 is a view of the entire suspenders, the shoulder straps being folded back upon 25 themselves.

Fig. 3 is an enlarged view of the back portion of the suspenders, and

Fig. 4 is a view of half of the portion of 30 the suspenders shown in Fig. 3 on a much larger scale.

These suspenders comprise two shoulder straps, indicated at 11, which are independent of each other in the respect that they do not cross each other nor are they attached 35 directly to each other. These straps are made of any suitable webbing and are adjustable as to length by means of a common form of adjusters 12 on the end of a loop 13 which extends through a flattened eye 14 40 to which is attached in any suitable manner the front ends 15, each provided with buttonhole tips 16 for securing the same to the garment. The back end of each strap 11 is secured to a flattened eye 18 to which 45 is pivotally connected by means of a headed pin 19 a grooved upper guide 20 through which slidably extends a round cord 21 forming a part of what may be termed the back adjuster generally indicated at 22.

The cord 21 is provided with two downwardly extending legs 23 which terminates in buttonhole tips 24 by means of which the adjuster is secured to the garment. The cord passes through the upper guides 20 55 and is formed into a loop 25 between the legs 23, such loop being formed by loop guides 26

through which the cord slidably extends. Each loop guide 26 is pivotally mounted by means of a headed pin 27 to a clasp or pivot member 28 which is clamped or otherwise secured in fixed relation to the cord 21.

Slidably mounted on the loop between the loop guides 26, is a pair of slip bands 30 which are movable on the cord being for the purpose of spacing apart the legs of the adjuster as there is a tendency for the straps to come together in the back when worn by persons having square shoulders. The two lower ends of the adjuster are spaced apart by a tie strap 31 which extends through the 70 ears 32 secured to the cord and upper end of the straps 24, such tie strap being provided with an adjuster 33 of any common form so that the distance between the legs of the adjuster may be adjusted to suit the wearer.

It will be noted that the shoulder straps which may be of elastic or non-elastic material pull upwardly on the back adjuster, the cord sliding through the upper guides and the loop guides to accommodate the position 80 of the straps according to the movement of the person wearing the suspenders, that is, an entirely free adjustment is provided as the two sides of the adjuster correspondingly shorten and lengthen to accommodate the 85 change of position of the straps. In no position is any pressure exerted on the middle of the back, the strain being in all cases in the line of extension of the straps.

I claim as my invention:

1. A pair of suspenders comprising a pair of shoulder straps; attaching means connected to the front ends of said straps; upper guides secured to the back end of said straps; a looped cord slidably extending 95 through said guides; a pivot member secured to each leg of said cord; a loop guide on each pivot member through which the loop in the cord slidably extends; slip bands on said cord between said loop guides; an adjustable tie strap connecting the legs of the cord together; and a buttonhole tip on each end of said cord.

2. A pair of suspenders comprising a pair of shoulder straps; attaching means connected to the front ends of said straps; upper guides secured to the back end of said straps; a looped cord slidably extending through said guides; a pivot member secured to each leg of said cord; a loop guide on each pivot member through which the loop in the cord 110 slidably extends; slip bands on said cord be-

tween said loop guides; and a buttonhole tip on each end of said cord.

3. A pair of suspenders comprising a pair of shoulder straps; attaching means at the front end of said straps; and an adjuster at the back end of said straps having garment attaching means consisting of a looped cord slidably connected to the back end of said

straps; and a pair of loop guides fixed to said cord for slidably engaging the looped portion of the cord.

In testimony whereof, I have hereunto set my hand at Los Angeles, California, this 10th day of May, 1921.

JOHN T. WATTS.
